UNITED STATES PATENT OFFICE.

ALEC J. GERRARD AND PARVIN WRIGHT, OF CHICAGO, ILLINOIS; SAID WRIGHT
ASSIGNOR TO SAID GERRARD.

PORTABLE WIRE TENSIONING AND TWISTING MACHINE.

Application filed June 14, 1922. Serial No. 568,301.

This invention relates to wire tying machines of comparatively light weight, and capable of manipulating comparatively very heavy wire, and has for its object to provide a machine of this character which will be simple in construction, certain in action, and less costly to manufacture than those heretofore proposed.

With these and other objects in view, the invention consists in the novel details of construction, and combinations of parts more fully hereinafter disclosed and particularly pointed out in the claims.

Referring to the accompanying drawings forming a part of this specification, in which like numerals designate like parts in all the views:

Fig. 1 is a side elevational view of a machine made in accordance with this invention;

Fig. 2 is a view of the knot tied by this machine;

Fig. 3 is a top plan view, partly in section, of the parts shown in Fig. 1;

Fig. 4 is a sectional detail view, taken on the line 4—4 of Fig. 1, looking in the direction of the arrows;

Fig. 5 is a sectional view taken on the line 5—5 of Fig. 1, looking in the direction 30 of the arrows;

Fig. 6 is a sectional view taken on the line 6—6 of Fig. 5;

Fig. 7 is a sectional detail view taken on the line 7—7 of Fig. 6, looking in the direction 35 of the arrows;

Fig. 8 is a perspective view of a portion of the operating lever shown in Fig. 5;

Fig. 9 is a sectional view, taken on the line 9—9 of Fig. 1, looking in the direction 40 of the arrows;

Fig. 10 is a view of the parts shown in Fig. 9, after one bight of the wire has been cut;

Fig. 11 is a view taken on the line 11—11 45 of Fig. 1, looking in the direction of the arrows;

Fig. 12 is a view of the parts shown in Fig. 11, after another bight of the wire has been cut; and

Fig. 13 is a view of a wire holding post.

1 indicates any suitable framework provided with the vertically extending portion 2, in which is mounted the main operating shaft 3, provided at its lower end with the

worm gear 4 meshing with the twisting pin- 55

ion 5, provided with the twisting slot 6 as best shown in Figure 5. The said frame- 60

work 1 may be divided into two parts along the line 7, and the front portion of the ma- 65

chine is provided with the extending lower lip 8 and the upper lip 9, forming a slot 10, between them, with which the slot 6 in the pinion 5 is adapted to register. The upper 70

front portion 11 of the framework is pro- 75

vided with a pair of projecting lugs 12 in which is mounted the operating shaft 13

having the eccentrically disposed pins 14 and 15 adapted to actuate the cutters 16 and 17 respectively. Also mounted in said 80

framework adjacent the cutter 17 is the wire holding post 18 and adjacent the cutter 16 is mounted likewise the wire holding post 19. At the upper end of the extension 2 of the framework is securely mounted the sup- 85

porting bracket 20 provided with the de- 90

pression 21 in which is placed the Geneva stop disk 22 and which is secured to the bracket 20 as by the screw means 23. Se- 95

cured to the upper end of the shaft 3 is the hub 26 of the operating lever 27, provided with the handle 28, all as will be clear from the drawings. Said handle 27 is provided 100

with the lugs 29, in which is mounted the lever 30, as by the pin securing means 31. A spring 32 holds the operating end 33 of 105

said lever in the elevated position shown in Figure 5, and its other or reduced end 34 passes through a hole in a vertically mova- 110

ble stop pin 35 which passes down through the hub 26 of the lever 27, and is adapted 115

to enter the various slots 37 in the disk 22, and to move said disk through a predeter- 120

mined angle for each complete rotation of the lever 27.

That is to say, when the lever 27 is ro- 125

tated continuously in one direction, the stop pin will successively enter the various notches 37 of the disk 22 and will turn said 130

disk until the blank portion 38 thereof comes opposite said stop pin 35, whereupon 135

the pin can no longer enter said notches 37, and the rotation of the lever 27 will cease. 140

When this happens, the operator will know that the number of twists he wishes to put 145

in the wire has been completed.

At the end of the frame, opposite the post 150

18, is mounted the vertically disposed oper- 155

ating shaft 50 provided at its upper end

with the operating lever 51, having the handle 52 and at its lower end with the worm gear 53 meshing with the worm 54 carrying the enlarged tension head 55, provided with the slots 56 adapted to receive the wire, as will presently appear. The shaft 50 is provided with the ratchet 57, and the framework is provided with the holding pawl 58, as best shown in Figure 3.

10 The operation of this machine is as follows: The flat surface or bottom 65 of the machine is placed upon the top surface 66 of the box or package 67 to be wired, and the extreme end 60 of the banding wire 61 is conveniently inserted in the notch 62 of the holding post 18, whereupon the bight 64 of said wire is passed into the slot 10 of the frame, as well as into the slot 6 of the twisting pinion 5, and out of said slot 10 of the frame through the holding post 19, whence it passes around the box or package 67 to be wired, and the wire 61 is then returned to the holding post 18, all as will be clear from Figures 1, 3 and 5.

15 25 The other bight 69 of said wire 61, after again reaching the holding post 18 and passing through the slotted portion 68 thereof, see Figure 13, passes into the slot 10 of the frame, and into the slot 6 of the twisting pinion 5, and out of said slot 10 through the holding post 19, whereupon said bight 69 passes into one of the slots 56 of the tensioning head 55, as best illustrated in Figures 1 and 3.

30 35 The lever 51 is now rotated to turn the tensioning head 55, which winds up the bight 69 and puts a very considerable tension on the wire. In fact, so great is the tension that may be put upon the wire 61, that its slack is completely taken up around the box and its bights cut into or sink into the edges of the box, so that the package is gripped very firmly indeed. Owing to the power that may be developed through the 40 45 worm 53 and worm gear 54, this tension may be made very great, and therefore a very large sized wire 61 may be employed notwithstanding the fact that the entire machine is comparatively very light. While the 50 bights 64 and 69 of the wire 61 are thus held under a heavy tension, the twisting lever 27 may be operated. This lever carries the vertically movable locking pin 35, as above described, which fits into a notch 70 in the bottom of the recess 21, with which the bracket 20 is provided, see Figure 7.

55 Said notch 70 is inclined as illustrated, and is provided with the vertical shoulder 90 against which the pin 35 takes when the motion of the lever 27 is reversed. It thus results that after the lever 27 has made a predetermined number of complete turns, depending upon the number of notches 37 in the disk 22, the stop pin 35 comes up 60 65 against the blank surface 38 of the disk 22,

and the twisting operation automatically stops. The number of notches 37 that are provided in the disk 22 depend upon the number of complete twists that it is desired to place in the knot, and also upon the ratio 70 of the twisting gears.

It is very important that when the twisting operation is completed, however, that the slots 6 and 10 should be in register, in order that the knot may be readily removed from 75 the machine. To accomplish this, the parts are so proportioned that a slight overtwist of the knot may be had, so that when the lever 27 is stopped in the manner above described, the resiliency or recoil of the parts 80 will turn the slot 6 backward and bring it into register with the slot 10. At the same time, this recoil of the bights 64 and 69 will serve to loosen the grip exerted by the slot 6 and will thus render the knot more easy 85 to be removed. In the meantime, the motion of the lever 27 can never be reversed after a complete rotation has been made, because the pin 35 would slide down the incline, of the notch 70 and come up against the shoulder 90 of said notch, and thus prevent the lever 27 from being turned back. The prevention of the lever 27 from being turned backwards prevents the operator from unintentionally untwisting the knot and thus 90 jamming the parts in the machine. The twisting operation having been thus completed and the pin 35 being brought up against the surface 38, as illustrated in Fig. 6, it is not possible to move the lever 27 in 100 either direction. Therefore, to unlock the parts to start a new operation, it is necessary to depress the lever 30 and raise the pin 35 a distance equal to the thickness of the disk 22, whereupon the lever 27 may be 105 turned and whereupon the depending end of the pin 35 will take against the lug 23 on top of said disk 22, see Figs. 5 and 6. A further turning of the lever 27 will now rotate the disk 22 with the said lever 27, and 110 thus will the blank space 38 be taken out of the path of the pin 35, and the parts be brought into position, ready for another operation.

In other words, it will now be clear that 115 the disk 22 and the pin 35 constitute a timing mechanism by which only a predetermined number of turns may be imparted to the bights 64 and 69, and by which one can not reverse the twisting operation, and un-twist the knot and thus jam the machine.

In order to accommodate the lug 23, the hub 26 is cut away as at 91, and the shoulders 92 are rounded off, as illustrated, in order to permit the ready passage of the lug. Below the main hub portion 26 is the disk like portion 95, which may be integral with the hub or otherwise rigid therewith, and which enters the curved cut away portions 96 of the disk 22 in order to lock the 125 130

said disk, except when the pin 35 is turning the same, all as will be readily understood, from the principles of the well known Geneva stop mechanism.

5 The two bights 64 and 69 of the wire having been thus twisted together, as illustrated in Figure 2, the cutting lever 75 is turned from the position shown in Figure 9 to that shown in Fig. 10, whereupon the short shaft 13 is rotated through an angle of 180°. This 10 rotation of the shaft 13 causes the pins 14 and 15 to depress respectively the vertical reciprocating cutter bars 16 and 17 on the sides of said posts 19 and 18 that are nearest 15 the twisting pinion 5. The cutter bar 17 is provided with the cutting edge 76, which overlies the bight 64 of the wire and with the notch 77 which overlies the bight 69 of the wire, so that when said cutter bar 17 is 20 depressed only the bight 64 of the wire will be severed, as will be plain from the position of the parts shown in Fig. 10. In the same way, when the cutter bar 16 is depressed, its cutting edge 80 which overlies the bight 69 25 of the wire will sever said bight only, and its notch 81 will prevent the bight 64 from being severed.

The result is that the ends of the bights 64 and 69 are simultaneously cut off very 30 close up to the twisted portion of the wire, indeed. In fact the cut ends of the bights 64 and 69 are positioned at the very terminations of the twisted portions of the knot, thus making a neat and efficient knot without 35 any projecting ends which are liable to tear boxes or packages which are moved over said knot. It should be mentioned, of course, that the slots 62 and 68, see Fig. 13, with which each of the posts 18 and 19 are 40 provided, hold the two bights 64 and 69 from turning during the twisting operation, and thus is the twisting pinion 5 enabled to twist the wire into the form shown in Fig. 2.

It is an important feature of this invention 45 that the power shaft 3 extends up above the machine in a vertical direction instead of horizontal, for it enables the operating handle 28 to be located above the package being wired, instead of to one side thereof, which has a very decided advantage where 50 the room is small and where the most convenient place to apply the power is on the top of the package, which often happens.

In addition to this, in dealing with very 55 large and heavy wires, as is the case here, and when employing a very light machine, as is also the case here, the vertically inclined power shaft enables one to employ worm gears to drive the twisting pinion, which has a decided advantage in that the power delivered is very great, and these gears are more or less self-locking, so that the operator does not have to be so careful as heretofore in making his twisted knot. 60

65 The ball bearings 98 at the bottom of the

power shaft 3 are also important, in a mechanism which delivers as much power as does this machine.

The same remarks apply to the ball bearings 99 at the bottom of the shaft 50. A further important feature of this invention resides in the fact that the bottom of the frame is smooth, so that the machine can freely slide or move over the top of the package being wired, and thus adjust more evenly the tension on the wire, and a still further important feature resides in the curved turned up portion 100, of this bottom framework, which enables one to tip the machine forward after the knot is tied, and thus utilize the tension which is already in the wire to disengage the wire from the machine. That is to say, a little consideration will show that the two bights of wire 64 and 69 after they have been twisted together, are necessarily under a very great tension, and therefore if given a chance to slide out of the slots 6 and 10, they will tend to do so. Accordingly, by rounding the frame as at 100, a machine can be bodily tipped and this tension of the wire utilized to disengage the knot after it is tied. 85

It is obvious that those skilled in the art may vary the details of construction as well as the arrangement of parts without departing from the spirit of the invention, and therefore we do not wish to be limited to the above disclosure, except as may be required by the claims. 90

What we claim is:

1. In a wire tying machine, the combination of means for holding parallel bights of wire, means for tensioning said wire, a slotted pinion for twisting said bights together, hand-operated means for rotating said pinion, a timing means comprising a slotted rotating disk actuated by said hand-operated means for automatically stopping the twisting motion of said pinion-rotating means, and a pair of cutters for serving each bight of the wire after the twisting operation, substantially as described. 105

2. In a wire tying machine, the combination of means for holding two bights of a wire, means for tensioning said bights, hand-operated means for twisting said bights together, and automatic means comprising a movable pin and a slotted rotating disk actuated by said hand-operated means for stopping the twisting operation after a predetermined angular motion has been imparted to said bights, substantially as described. 115

3. In a wire tying machine, the combination of means for holding two bights of a wire, means for tensioning said bights, means for twisting said bights together, and automatic means for stopping the twisting operation after a predetermined angular motion has been imparted to said bights comprising a slotted rotating disk having a plu- 125

rality of slots and a blank space, and a movable pin adapted to enter said slots during the twisting operation and to take against said blank space at the end of said operation, substantially as described.

4. In a wire tying machine, the combination of a frame provided with a power shaft extending upwardly from said frame and inclined to the vertical, a twisting gear operated by said shaft, a hand-operated means connected to said shaft, means associated with said hand-operated means for limiting the rotations of said shaft, and means carried by said hand-operated means for releasing said shaft after its rotations have been limited, substantially as described.

5. In a wire tying machine, the combination of a frame provided with a power shaft extending upwardly from said frame and inclined toward the vertical, a twisting gear operated by said shaft, a hand-operated means connected to said shaft, means comprising a slotted disk associated with said hand-operated means for limiting the rotations of said shaft, a ball-bearing on which the lower end of said shaft turns, and means comprising a spring pressed lever carried by said hand-operated means for releasing said shaft after its rotations have been limited, substantially as described.

6. In a wire tying machine, the combination of a frame, a power shaft extending upwardly from said frame, a lever for actuating said power shaft, a pair of wire holding posts each adapted to hold parallel disposed wires and having flat sides, a wire twisting means operated from said power shaft and located between said posts, a pair of wire cutters movable up and down in contact with the flat sides of said posts nearest said wire twisting means and adapted to act comple-

mentally to said posts in severing the wire, an oscillating shaft provided with eccentrics adapted to actuate said cutters, and an oscillating lever for actuating said shaft, substantially as described.

7. In a wire tying machine, the combination of means to hold parallel bights of wire to be twisted, a power shaft extending upwardly from the machine, a worm on the lower end of said shaft, a ball-bearing on which said shaft turns, a twisting means comprising a worm-gear meshing with said worm for twisting together said bights, a tension head comprising a worm and gear adapted to strain the wire before the twisting action, and means for cutting both of said bights at the end of the twisting operation, substantially as described.

8. In a wire tying machine, the combination of a frame provided with a smooth bottom, a power shaft extending upwardly from said frame, a pair of slots inclined to said bottom, a turned-up edge intermediate said bottom and said slots, and an upwardly extending portion adapted to facilitate the rocking of said frame on said turned up edge, a twisting pinion provided with a slot adapted to register with said first-named slots, a power shaft disposed in said upwardly extending frame portion to operate said pinion, and means for automatically stopping the slot carried by said pinion in register with said frame slots at the end of the twisting operation, whereby said frame may be readily tipped when the twisting action is completed and the knot disengaged from the machine.

In testimony whereof we affix our signatures.

ALEC J. GERRARD.
PARVIN WRIGHT.
